UNITED STATES PATENT OFFICE.

GEORGE S. PRICHARD AND JAMES W. TAYLOR, OF GOLDSBOROUGH, NORTH CAROLINA, ASSIGNORS OF ONE-FIFTEENTH TO JAMES EDGAR SMITH, OF WASHINGTON, DISTRICT OF COLUMBIA.

BAG-STRINGING MACHINE.

SPECIFICATION forming part of Letters Patent No. 602,915, dated April 26, 1898.

Application filed July 7, 1897. Serial No. 643,711. (No model.)

To all whom it may concern:

Be it known that we, GEORGE S. PRICHARD and JAMES W. TAYLOR, citizens of the United States, residing at Goldsborough, in the county 5 of Wayne and State of North Carolina, have invented a new and useful Bag-Stringing Machine; and we do hereby declare the following to be a full, clear, and exact description of our invention, such as will enable others skilled 10 in the art to which it appertains to make and use the same, reference being had to the accompanying drawings.

Tobacco-bags, salt-bags, flour-bags, and the like are provided at their mouths with shirring or puckering strings, which when drawn 15 taut close the bags and retain their contents. These shirring-strings are usually inclosed in a hem formed at the mouth of the bag by turning over the edge of the bag material and 20 stitching or otherwise fastening the same. Two strings having their knotted ends extending from opposite sides of the bag-mouth are generally used, and the bag is closed by pulling upon these free ends in opposite directions. At the present time these strings are 25 inserted by hand, a bodkin serving to draw the strings through the circular loop or hem at the mouth of the bag.

This invention is an improvement in bag- 30 stringing machines, and has for its objects to provide a machine which will string bags rapidly, accurately, and cheaply, and yet be simple in its structure, easily operated, and inexpensive to manufacture.

With these objects in view the invention resides in the various novel details of construction, in the combinations of the parts, and in the machine as an entirety.

In the accompanying drawings, to which 40 reference is made and in which like letters indicate corresponding parts, Figure 1 is a view showing the machine in side elevation. Fig. 2 is a view showing in plan a portion only of the machine. Figs. 3, 4, 5, 6, 7, 8, 45 and 9 are views showing in perspective certain parts of the machine, giving them more in detail than as elsewhere shown. Figs. 10, 11, and 12 show in plan one of the details of arrangement of the parts, illustrating the 50 manner in which the bags are strung. Fig.

13 shows a modification of one of the parts, and Fig. 14 shows how the string is dropped from the needles and a new one inserted.

In the drawings the letter A indicates a frame supporting the machine, B a power-shaft for communicating motion to it, and C and D the main divisions of the apparatus itself, C designating the needle mechanism and D a wheel for presenting bags to the needles one after another, the two devices being operated from the main power-shaft and so synchronized that a bag is presented to the needles for each complete forward-and-backward movement of them, another bag following in time for their next reciprocation.

The power-shaft is supported by the standards b or in any suitable manner and is driven by means of the pulley b' or otherwise, as may be convenient. A wheel or the like B' is secured upon the shaft at one end and carries 70 a grooved way b² across its center, wherein one end of the crank-arm b³ is secured by a pivot-pin, the stroke of the said crank-arm b³ being regulated by adjustment in the said grooved way b². The power-shaft carries also 75 a cylinder B², secured upon it, and this cylinder has a cam-groove b⁴ in its face.

The needle mechanism C consists of ways c, bolted to the frame, spaced from each other at their tops and bottoms, and these ways 80 support a needle-carriage c', which is connected by a pivot-pin on its under side with the crank-shaft b³. The needle-carriage has longitudinal grooves c² in its sides, which embrace the L-shaped tops c³ of the ways, thereby restricting the carriage to longitudinal movement along the ways. The length of the longitudinal movement of the needle-carriage is regulated by adjusting the stroke of the crank-shaft b³. Taking the parts as shown 90 in Fig. 1, each revolution of the power-shaft B will produce one complete forward-and-backward movement of the needle-carriage c'. The needles themselves, c⁴, have spring-eyes c⁵ and are secured to their carriage in 95 any suitable manner, such as by plate and tap-bolt, as shown in Figs. 7 and 8. They are usually rather blunt and are held with their spring-eyes uppermost for ease in inserting the string. The ways c have a cross- 100

piece c^6 between their forward ends, which serves to space them and also as a bed for the spring-catch c^7 , which is adapted to engage depressions in the rim of the wheel D and hold the same from accidental movement. This spring-catch c^7 has a rounded head, as shown in Fig. 6, and the depressions it engages have gentle slopes, so that force exerted upon the wheel will release it from the action of this detent, the purpose to be accomplished by which is merely to steady the wheel when not caused to revolve by the mechanism to be described.

The wheel D is suitably mounted in a horizontal position upon the frame A by the axle d , so that its axis lies in a vertical plane passing through an imaginary line formed by a point midway between the needles during the reciprocation of the needle-carriage c' . This wheel consists of a hub d' , spokes d^3 , which extend therefrom, and a rim or periphery d^3 , secured to the outer ends of the spokes. These spokes are bent at right angles to themselves near their outer ends, and the rim is secured to them in any suitable manner, such as by the brackets d^4 , so that the rim is raised above the plane of the main body of the spokes and is approximately in the horizontal plane of reciprocation of the needle-carriage c' , nearly touching the cross-piece c^6 in the ways which support said carriage. The rim d^3 is an annular plate of metal or the like and has indentations d^5 radially opposite each other in its inner and outer edges, and each pair of these indentations corresponds in radial position with a spoke, so that a plane passed vertically through any pair of them would also pass through the axis of the wheel and the longitudinal center of a spoke.

The indentations d^5 upon the outer edge of the rim are adapted to receive the detent or spring-catch c^7 , mounted in the cross-piece c^6 of the ways c of the needle mechanism, thereby maintaining the alinement of the spokes d^3 with the central line of reciprocation of the needle-carriage.

A rigid standard d^6 (seen best in Fig. 5) is secured to the upper face of the rim between each pair of indentations, and a spring-standard d^7 is adjustably secured upon each spoke, so that it may be placed at any required distance from the inner edge of the rim, the inner indentations d^5 allowing the spring-standard d^7 to approach close to d^6 . These two standards form the bag-holding device, the bag X, after manufacture, being placed mouth downward upon them, the spring-standard d^7 stretching the bag, so that its sides lie nearly parallel to each other. Stops d^8 may be placed upon the standards to regulate the position of the bag, so that the hem x of the bag will lie on either side of the standards in direct lines with the lines of reciprocation of the needles c^4 . It is to be noted in this connection that the thickness of the standard d^6 is somewhat less than the distance between the needles c^4 , whereas the width of the spring-

standard d^7 is nearly or quite equal to this distance.

To insure the entry of the needles c^4 into the hem x as they move forward to the bag, eccentrically-mounted gripping-hooks d^9 are provided, their function being to catch the outer webs of the hem on either side of the standard d^6 , stretch the same away from the inner webs, and guide the needles to the points in the material punctured by them. These hooks have grooves d^{10} , which are adapted to guide the needles, and they are pivoted eccentrically upon the rim d^3 by means of the cam-levers d^{11} . Each cam-lever consists of a slotted arm d^{12} , which straddles a guide-pin d^{13} , an enlarged head d^{14} , inclosing a disk revolving upon a pivot d^{15} away from its center and having a pin or lug d^{16} projecting through an opening in the rim d^3 . The curve described by the hooks d^9 can be regulated as to its length and angle by adjustment of the pin d^{13} , so that the hooks may be moved first toward the bag-hem to catch the outer web thereof, and then away from it to stretch this outer web from the inner web, thereby opening channels in the hem for the passage of the needles. This is the movement illustrated in Figs. 10, 11, and 12, where the action of the gripping-hook is exaggerated the more clearly to show the same.

To move each pair of eccentrically-mounted gripping-hooks at the same time, the lever d^{17} is used. This lever consists of a handle d^{18} , from which extend forked arms d^{19} , which are pivoted on either side of the wheel-spoke d^2 , whence they are bent upwardly to form bell-crank arms and have their extremities extended laterally as slotted arms d^{20} . These laterally-extending slotted arms d^{20} loosely engage with in them the lugs or pins d^{16} of the eccentrically-mounted cam-levers d^{11} . A spring d^{21} normally presses the handle d^{18} upward from the spoke d^2 , forcing the lever to assume the position indicated in Fig. 3, while a spring-catch d^{22} , secured to the spoke, is adapted to hold the lever when depressed. Every depression of the lever d^{17} causes the gripping-hooks to go through the positions shown successively in Figs. 10, 11, and 12, and when the hem of the bag has been stretched, as shown in Fig. 12, the spring-catch d^{22} holds the lever d^{17} , and therefore the gripping-hooks d^9 , in position until released by hand. It will be observed that the wheel D carries a number of bag-holding and hem-opening devices corresponding to the number of spokes in the wheel. These devices are all alike, and the object of this multiplication of similar parts is to enable one operator to place the bags upon the standards and set the gripping-hooks in the bag-hem at one part of the wheel while the needles, fed with string by another operator, are stringing the bag on the part of the wheel in line with the reciprocating needle-carriage.

The wheel D is rotated in one direction by intermitting impulses received from the main

power-shaft through the mechanism shown in Figs. 1 and 2. In the surface of the cylinder B² is cut a cam-groove b⁴, which is adapted to receive a loose pulley b⁵, attached to one end 5 of a lever b⁶, which is bent at an angle to itself and pivoted vertically at b⁷ to the frame A, between which and the spokes of the wheel D it is extended horizontally in the arm b⁸. At the extremity of this arm a spring-pressed 10 latch b⁹ extends upwardly far enough to encounter the spokes d³, the beveled face of the latch easily passing the spokes—i.e., the latch-spring being weaker than the spring of the 15 detent c⁷—and the flat or rounded side of the latch impinging against the said spokes when the lever moves in the opposite direction. The wheel may be caused to revolve either toward the right or toward the left by means of this 20 spring-pressed latch, the cylinder B² being capable of longitudinal movement along the power-shaft by means of a spline or the like. The cam-groove b⁴ is so cut as to cause the lever b⁶ to oscillate through the paths shown 25 in Fig. 2, and the curves of this groove are so timed with the revolution of the crank-wheel B' that the bag-wheel D is moved spoke by spoke between the time when the needles recede from the guides d¹⁰ in the gripping-hooks d⁹, the wheel D being at rest during the time 30 the needles complete their forward movement and accomplish so much of their backward movement as carries them out of the range of the said gripping-hooks. As shown in Fig. 35 2, when the arm b⁸ is in the position indicated by the solid lines the needles, which are not shown, have just receded from the gripping-hooks d⁹, and the lever, guided by the cam-groove, is about to begin an oscillation to the right, carrying with it the particular spoke of 40 the wheel against which the flat or rounded side of its spring-pressed latch is pressed. In this movement the force exerted by the lever upon the wheel is sufficient to drive the detent c⁷ back against its spring, and the movement is continued until the said detent presses 45 forward into the next indentation d⁵, when the lever occupies the position indicated in dotted lines in the said Fig. 2. By this time the needles have completed their backward 50 movement and have accomplished so much of their forward movement as will bring them in close juxtaposition to the gripping-hooks d⁹. A reverse curve in the cam-groove now carries the oscillating lever back again to the 55 position shown in solid lines, while the needles advance forward and then retract, the spring-pressed latch b⁹ passing under the next spoke of the wheel to the left without moving it. This operation continues indefinitely, the 60 needles reciprocating over one half of their course—i.e., that portion thereof within the outer edge of the rim of the wheel D—while the wheel is at rest and reciprocating over the other half of their course—i.e., that lying 65 without the outer rim of the wheel D—while the wheel moves over an angle equal to that measured between each pair of spokes.

Instead of using a pair of eccentrically-mounted gripping-hooks d⁹, secured to the rim d³ near each rigid standard d⁶, and operating the same by means of levers d¹⁷ the device indicated in Fig. 13 may be used. This figure is merely a diagram, and some of the parts essential to its operation are omitted. As here shown, a single pair of gripping-hooks d⁹ are eccentrically pivoted on the under side of a plate (not shown) secured to the needle mechanism above the path of reciprocation of the needles. Cam-levers d¹¹, similar to those already described, control the paths 70 of these gripping-hooks, and these cam-levers are moved either by hand or by machinery to grip each bag immediately the detent c⁷ has engaged the indentation d⁵. As shown in Fig. 13, this is accomplished by means of cam-wheels y, secured on an auxiliary shaft y', and springs y² press the cam-levers d¹¹ backward, thus releasing the bag whenever the force exerted by the cam-wheels is released. 75

The operation of the device is as follows: 80 Bags are placed with their mouths downward upon the standards secured to the wheel D, the hems of all the bags lying in one plane. The gripping-hooks are moved forward to grip the outer webs of the bags on either side 85 of each rigid standard and then stretch the same by moving apart from each other, a single depression of the lever d¹⁷ accomplishing 90 this movement, the spring-catch d²² holding the lever depressed. All of the standards being now provided with bags properly adjusted 95 to receive the needles, the power-shaft is caused to revolve. As the needles c⁴ move forward an operator standing at the side of the mechanism inserts within their eyes c⁵ a 100 piece of string somewhat less in length than twice the distance from the outer edge of the rigid standard c⁶ to the extremity of their forward movement. This string enters the needle-eyes by being pressed against the spring-tops of the same, the operator taking care 105 that an equal length of string extends on either side of the needles. The needles continue to advance and presently enter the hem x, being guided thereto by the grooves d¹⁰ in 110 the gripping-hooks d⁹. As the advance continues the portion of the string between the two needles is caught by the rigid standard d⁶, and the needles still going forward the string is finally dropped from their eyes, as indicated 115 in Fig. 14. The needles now have completed their forward movement, have dropped one of the shirring-strings, laying it within the hem at the mouth of the bag, and are ready to begin the backward movement. 120 Another string similar in length to the one just described is now inserted in their spring-eyes c⁵ in a manner similar to that just described, and as they are retracted through the bag the second string is laid within the 125 hem. As the needles recede from the outer edge of the wheel D the said wheel is given a portion of a revolution and presents another bag before the needle mechanism by the 130

means and in the manner heretofore described. As the bags are strung an operator standing on the side of the needle mechanism toward which the wheel is caused to revolve removes the strung bags and replaces them by those which are yet to receive shirring-strings.

It will be observed that, as described, two operators are contemplated as feeding the machine, one placing the bags upon the wheel and another threading the needles; but the number of operators needed with this machine is entirely dependent upon the rapidity with which it is driven.

It is to be noted that while gripping-hooks are provided to guide the needles into the hem at the mouth of the bag no device is provided to guide them in their exit at the other ends of the hem, and this is so for the reason that while it would be possible for the needles to make a false entry into the hems or to miss them altogether, still when once within these hems the hems themselves are guides to the blunt needles, and the needles are forced to puncture the outer web of the hems when they reach the spring-standards d^7 . Having once punctured the bags at or near the standard d^7 , the needles when retracted merely retrace the forward movement and lay the second string in the same channels which received the first. The bags which are now provided with shirring-strings are finished by knotting the corresponding loose free ends of these strings.

In Fig. 9 is shown a needle-guide c^8 , which may be secured at any point on the ways c . This guide may or may not be used, but if used is to be placed just within the point of farthest retraction of the needles, so that the eyes c^5 will project beyond it.

Having thus fully described our invention, what we claim as new, and desire to secure by Letters Patent of the United States, is—

1. In a bag-stringing machine the combination with a frame, of a needle-carriage, needles, a wheel, bag-standards secured to said wheel on its rim in line with the spokes thereof, a power-shaft connected with the needle-carriage by a crank-shaft, a lever pivoted to the frame having one leg engaged by a cam-groove on the power-shaft and having its other leg provided with a spring-latch, the said spring-latch extending into the path of the wheel-spokes and being adapted to pass said spokes when oscillated in one direction and to move said spokes with it when oscillated in the other direction, indentations upon the wheel in line with the standards and spokes thereof, and a spring-detent adapted to engage the said indentations and hold the bag-standards nearest thereto in line with the central line of reciprocation between the needles.

2. In a bag-stringing machine, a frame, ways secured to said frame, a needle-carriage adapted to reciprocate within said ways, needles secured to said carriage, a power-shaft,

a crank-shaft pivoted to and connecting the said power-shaft and the needle-carriage, a wheel mounted upon the frame with its rim 70 nearly touching the aforesaid ways, the said rim lying approximately in the plane of reciprocation of the needles, and within about one-half of their forward thrust, the said rim having indentations on its outer edge which 75 are in radial alinement with the spokes of the wheel and have adjacent to them also in alinement with said spokes bag-holding standards, a spring-detent secured to the needle-ways and adapted to engage the indentations 80 in the rim of the wheel, a cylinder secured upon the power-shaft, a cam-groove in the said cylinder having its points of lateral departure lying within a plane approximately at a right angle to a plane passed through 85 that diameter of the power-shaft which coincides with a line connecting the center of said shaft with the center of the crank-pin when the crank is at its greatest thrust, a lever pivoted to the frame having one end engaged by 90 the said cam-groove, and having a spring-latch upon its other end, the said spring-latch projecting into the path of the spokes of the wheel, and adapted to move the wheel by said spokes in one direction through an arc 95 equal to that measured between said spokes.

3. In a bag-stringing machine, a needle-carriage, needles secured thereto, means for reciprocating the same, in combination with a wheel mounted approximately in the plane 100 of reciprocation of the said needles and within the path thereof, the said wheel being provided with bag-holding standards, gripping-hooks on either side of said standards, and means for revolving the said wheel by intermittent impulses through arcs equal to the distance between said bag-holding devices.

4. In a bag-stringing machine the combination with standards adapted to receive and hold the bags, of gripping-hooks adapted to 110 enter the hem of the bag and stretch the same away from the said standards.

5. In a bag-stringing machine, the combination with bag-holding standards, of gripping-hooks pivoted eccentrically on both sides of 115 said standards and adapted to move in a curve approaching the said standards until they nearly touch it and then to recede therefrom.

6. In a bag-stringing machine the combination with bag-holding standards of gripping-hooks pivoted on either side thereof, the said gripping-hooks being provided with needle-guides.

7. In a bag-stringing machine the combination with eccentrically-mounted gripping-hooks, one on either side of a bag-standard, of means adapted to move the said hooks toward the said standard at the same time.

8. In a bag-stringing machine the combination with a wheel, a power-shaft and a pair 130 of reciprocating needles, of bag-standards secured upon the rim of the said wheel having eccentrically-mounted gripping-hooks on either side of them, means for holding the

said standards in line between the said needles as they are thrust forward and retracted within the outer edge of the rim of the wheel, and means for moving said wheel over an arc equal to the distance between the standards upon it when the needles retract from the outer edge of its rim and before they enter it again.

In testimony whereof we have hereunto set our hands in the presence of two subscribing witnesses.
